(57) **CLAIM**

The ornamental designs for a heater blower, as shown and described.

DESCRIPTION

FIG. 1 is a perspective view of an ornamental design for a heater blower.

FIG. 2 is a front elevation view of the heater blower of FIG. 1.

FIG. 3 is a rear elevation view of the heater blower of FIG. 1.

FIG. 4 is a left side elevation view of the heater blower of FIG. 1.

FIG. 5 is a right side elevation view of the heater blower of FIG. 1.

FIG. 6 is a top plan view of the heater blower of FIG. 1; and, FIG. 7 is a bottom plan view of the heater blower of FIG. 1. The broken line illustrations of vents are shown for the purpose of illustrating optional structure of the article and forms no part of the claimed design.
